(57) **CLAIM**

The ornamental design for a ladder for a trampoline as shown and described.

DESCRIPTION

FIG. 1 is a front view of a ladder for a trampoline in accordance with the present design.

FIG. 2 is a left side view of the ladder for the trampoline shown in FIG. 1.

FIG. 3 is a right side view of the ladder for the trampoline shown in FIG. 1.

FIG. 4 is a rear view of the ladder for the trampoline shown in FIG. 1.

FIG. 5 is a top view of the ladder for the trampoline shown in FIG. 1.

FIG. 6 is a bottom view of the ladder for the trampoline shown in FIG. 1.

FIG. 7 is a front perspective view of the ladder for the trampoline shown in FIG. 1; and,

FIG. 8 is a rear perspective view of the ladder for the trampoline shown in FIG. 1.

The broken lines and unshaded surfaces enclosed by the broken lines show portions of the ladder for a trampoline that form no part of the claimed design.

1 Claim, 8 Drawing Sheets
